UNITED STATES PATENT OFFICE.

ARTHUR H. HAPPE, OF DETROIT, MICHIGAN, ASSIGNOR OF ONE-HALF TO SAMUEL C. MUMFORD, OF DETROIT, MICHIGAN.

ELECTRIC SAD-IRON.

979,291.

Specification of Letters Patent. Patented Dec. 20, 1910.

Application filed June 30, 1910. Serial No. 569,717.

To all whom it may concern:

Be it known that I, ARTHUR H. HAPPE, who am a citizen of the United States, residing at Detroit, county of Wayne, State 5 of Michigan, have invented a certain new and useful Improvement in Electric Sad-Irons, and declare the following to be a full, clear, and exact description of the same, such as will enable others skilled in the art 10 to which it pertains to make and use the same, reference being had to the accompanying drawings, which form a part of this specification.

This invention relates to electrically 15 heated sad irons, and has for its object an improved device of this type adapted to be heated through the medium of individually removable heating units, which, when suitably connected up in series, form a sufficient 20 resistance element to generate the degree of heat required for heating the polishing surface of the iron.

In the drawings:—Figure 1, is a perspective of the entire iron with the top casting member lifted from the bottom or polishing plate, and with portions of the latter broken away to show the various laminations. Fig. 2, is a plan of the polishing plate and the removable heating units. Fig. 3, 25 is a view from beneath of the under surface of the top or casing member of the iron. Fig. 4, is a side elevation of the polishing plate, and the heating elements located thereon. Fig. 5, is a broken away plan 30 view of a pair of adjacent heating elements. Fig. 6, is a similar view of a modified form of element. Fig. 7, is a perspective of a pair of heating units illustrating, in somewhat exaggerated proportion and spacing, 35 the contact of their adjacent terminals. Fig. 40 8 is a side elevation of the adjacent ends of a pair of heating units showing the relative position of the contacting resistance element ends; the raising of the top sheet of mica 45 at its end is exaggerated in degree.

The top casing A of the iron is adapted to be attached to the bottom or polishing plate B through the medium of the bolt C which engages in the threaded socket D 50 which rises funnel-like from the upper surface of the plate B. The shoulders E, which fit in corresponding recessed portions F in the under face of the casing member, insure the accurate fit of the two parts when they

are placed in contact with one another before the bolt C is screwed down.

Arranged adjacent to the edges of the polishing plate B, except at the rear, are a series of independently removable heating units G. Each of these units comprises a 60 non-conducting core member H, about which the resistance element J preferably a flat, ribbon-like strip is wound serially, after which there is placed against each outer face of the element non-conducting sheets K, 65 preferably of mica, which effectively insulate the strands of the resistance element from the adjacent parts of the iron. The end portions of these units G are preferably cut away as at L so as to engage about the 70 shoulders E in the upper surface of the polishing plate, and thus be held in place against lateral displacement. The projecting ends M and N of the several units G project from the protecting mica sheets to 75 such an extent and in such position as to be placed in contact with one another when the various units are assembled, and the ends of the rearward units are in position to be engaged by the resilient clip members P, 80 which depend against them from the top portion A of the casing, through whose outer shell their continuations extend to suitable binding posts or clips O, to which the terminal of the current cord can easily be attached. By arranging the units near the edge of the polishing plate, I secure the location of the greatest heat at the edge of the iron and at its forward point, which is highly 85 desirable, inasmuch as the center is most easily heated even under these conditions, because it receives heat from both sides, whereas, the heating of the edges is by far the most desired part. The under shell or ceiling T of the casing member A lies so closely adjacent to the upper surface of the polishing plate B when the parts are fully assembled 90 that it bears strongly upon the upper surface of the several heating elements, thereby insuring the contact of the exposed terminals of the several parts.

In Fig. 6 is shown a slightly modified form of resistance element in which the element W is stamped from a single sheet of metal, the space between its individual 105 lengths V being cut away to such an extent as to merely leave a sinuous metal path along which the current can travel. In this

type there is no central core member H, but there are the usual mica inclosing plate K and the cut-away portions L. Both devices, however, are equally adapted to the arrangement shown in Fig. 2 wherein two units are caused to overlap at the forward point, thus providing a maximum heat at that point it is most desired. Either type of unit is capable of independent removal and renewal without disturbing the adjacent units to any appreciable degree, thus a package or supply of these units can be furnished to each purchaser of the iron and be saved the trouble and expense of subjecting the device as a whole to expert repair when any one of the units burns out.

What I claim is:—

1. In an electric sad iron, in combination with a bottom plate provided with a plurality of upwardly extending shoulder members near the periphery thereof, a top casing piece adapted to fit thereover, a series of independently removable heating units interposed between said bottom plate and top casing piece, and in engagement with said shoulder members, whereby they are held in place on said bottom plate, each unit comprising a pair of inclosing insulating plates, a central non-conducting core, and a resistance element wound thereabout with its ends projecting outside said insulating plates for contact with the corresponding parts of adjacent units, and a pair of terminal parts insulated at their outer ends extending through the walls of said casing into contact with the exposed ends of the resistance elements of the end units of the series, substantially as described.

2. In an electric sad iron, in combination with a bottom plate provided with upwardly

projecting shoulder portions, a plurality of independently removable laminated heating units adapted to fit about said shoulder portions and to be held thereby in position adjacent the edge of the bottom plate, each of said units comprising a non-conducting core, a resistance element wound thereabout, and a pair of insulating plates arranged over the sides thereof, the ends of the resistance element projecting outside of said insulating plates so as to contact the corresponding terminals of other individual elements when arranged upon said bottom plate, substantially as described.

3. In an electric sad iron, the combination of a separable casing and polishing plate member having anchorage shoulders projecting from the upper face of the polishing plate portion and correspondingly recessed parts in the under surface of the casing, a pair of contact clips insulated at their outer ends engaging through the wall of the casing, and a series of independently removable heating units arranged in electrical contact with one another and against said anchorage shoulders, and with their end members in contact with said clips on the peripheral portion of the top surface of the polishing plate member, each element comprising a pair of external insulating plates, a central core member, and a resistance element wound thereabout and protected except as to its projecting ends by said insulating plates, substantially as described.

In testimony whereof, I sign this specification in the presence of two witnesses.

ARTHUR H. HAPPE.
